(57) **CLAIM**

The ornamental design of a y-adapter, as shown and described.

DESCRIPTION

FIG. 1 is a perspective view of a y-adapter showing our new design.

FIG. 2 is a top elevation view thereof.

FIG. 3 is a bottom elevation view thereof.

FIG. 4 is a right side elevation view thereof, the left side being a mirror image thereof.

FIG. 5 is a front plan view thereof; and,

FIG. 6 is a back plan view thereof.

The ornamental design element between the arms of the y-adapter incorporates a trademark of Kyphon Inc., 1350 Bordeaux Dr., Sunnyvale, CA 94089.
